UNITED STATES PATENT OFFICE.

RALPH H. MCKEE, OF NEW YORK, N. Y.

MOTOR FUEL.

No Drawing.

Application filed January 16, 1922. Serial No. 529,771.

To all whom it may concern:

Be it known that I, RALPH H. MCKEE, a citizen of the United States, residing at New York, in the county of New York and State 5 of New York, have invented certain new and useful Improvements in Motor Fuels, of which the following is a specification.

This invention relates to motor fuel, and in its preferred embodiment comprises a 10 mixture of shale oil, benzol, and alcohol containing a small amount of ether.

In the making of motor fuels for internal combustion engines employing alcohol, it is customary to add a small amount of ether 15 to the mixture to increase the ease of starting the engine. The alcohol containing motor fuels most commonly used consist of substantially equal parts of petroleum products, commercial benzol and alcohol. The petroleum products are mostly gasoline, the commercial benzol contains benzol and a small amount of toluene, and the alcohol carries a small amount of ether. The percentage of ether present in the finished fuel will vary 20 according to its use, and whether it is to be used in warm or cold weather, but such fuels normally contain from 3 to 10 per cent of ether.

Motor fuels in which ether is present generally give trouble from two causes; they cause the engine to knock, and in the presence of alcohol, they form organic acids such as acetic acid. In the manufacture of ether, a small amount of ethyl peroxide is usually 30 formed, which reacts upon the alcohol to form organic acids. These acids cause corrosion in tank cars, storage tanks, and automobile cylinders.

I have found that where shale oil is substituted for petroleum products in the motor fuels heretofore described, a mixture will be obtained in which the disadvantages of the use of ether are overcome and the advantage of ease in starting is maintained. These shale oils are high in nitrogen bases, particularly in members of the pyridine and iso-quinoline series. I accordingly employ the more volatile or gasoline like fraction of shale oil in place of the corresponding fraction of well petroleum in the motor fuels heretofore described and obtain a fuel in which the knocking caused by the ether is overcome and the corrosive tendency of the fuel mixture is overcome. The gasoline like 45 fraction of shale oil employed is preferably the fraction having a gravity of .650 to .740

and distilling between 100° F. and 350° F. Such fractions have a flash point at quite low temperatures, even below 32° F. Such fractions, when of the unrefined shale naphtha, are strong odored, due to the presence of nitrogen bases. It has heretofore been necessary to add aniline or a similar substance to the fuel to prevent knocking or corrosion when ether is employed, but by 60 using the shale oil derivatives in place of the petroleum, the same result is obtained without additional cost.

In a typical embodiment of the invention, I employ about one-third shale oil distillate, 70 from which the pyridines and isoquinolines have not been removed, one-third benzol products consisting of commercial benzol and a small amount of toluene, and one-third alcohol consisting of alcohol and an amount of ether sufficient to form from 3 to 10 per cent of the entire mixture. The proportions may be varied within wide limits. Under some circumstances, the shale oil derivative 75 present may be employed in large percentages up to and in excess of 50 per cent, and the alcohol and benzol products may be accordingly decreased.

As a somewhat different method of practicing the invention, I have found that satisfactory results may be obtained by eliminating the benzol, in which case the alcohol content is preferably proportionately increased. In this embodiment of the invention, I prefer to employ absolute alcohol 80 rather than the 95 per cent alcohol ordinarily employed.

By providing such a mixture, using shale oil containing the nitrogen bases, the mixture overcomes the tendency of the ether to cause knocking and prevents corrosion of the engine cylinders, storage tank and tank cars by the formation of organic acids such as acetic acid.

While I have described in detail the preferred practice of my process, it is to be understood that the details of procedure, and proportion of ingredients may be widely varied, and that known chemical equivalents may be employed in place of the materials mentioned, without departing from the spirit of the invention or the scope of the subjoined claims.

Having thus described my invention, I 110 claim:

1. A mixed fuel for internal combustion engines comprising the gasoline like frac-

tion of shale oil having nitrogen bases therein.

2. A mixed fuel for internal combustion engines comprising the gasoline like fraction of shale oil having nitrogen bases therein and alcohol.

3. A mixed fuel for internal combustion engines comprising the gasoline like fraction of shale oil having nitrogen bases therein, 10 alcohol and ether.

4. A mixed fuel for internal combustion engines comprising the gasoline like fraction of shale oil having nitrogen bases therein, alcohol and ether, the ether being present 15 in approximately from 3 to 10 per cent of the fuel.

5. A mixed fuel for internal combustion engines comprising the gasoline like fraction of shale oil having nitrogen bases therein, 20 alcohol, ether and benzol.

6. A mixed fuel for internal combustion engines comprising the gasoline like fraction of shale oil having nitrogen bases therein, alcohol, ether and commercial benzol 25 containing toluol.

7. A mixed fuel for internal combustion

engines comprising the gasoline like fraction of shale oil having nitrogen bases therein, alcohol containing a relatively small amount of ether and benzol containing a 30 relatively small amount of toluol.

8. A mixed fuel for internal combustion engines comprising the gasoline like fraction of shale oil and alcohol.

9. A mixed fuel for internal combustion 35 engines comprising the gasoline like fraction of shale oil, alcohol and ether.

10. A mixed fuel for internal combustion engines comprising the gasoline like fraction of shale oil, alcohol, ether and benzol. 40

11. A mixed fuel for internal combustion engines comprising the gasoline like fraction of shale oil, alcohol containing a relatively small amount of ether and commercial benzol containing a relatively small 45 amount of toluol.

In testimony whereof I affix my signature in presence of two witnesses.

RALPH H. MCKEE.
